172,527

WINDSHIELD SCRAPER AND CLEANER

Melvin A. Wattles, Kearney, Nebr.

Application June 11, 1953, Serial No. 25,443

Term of patent 14 years

(Cl. D9—6)

To all whom it may concern:

Be it known that I, Melvin A. Wattles, have invented a new, original, and ornamental Design for Windshield Scraper and Cleaner, of which the following is a specification, reference being had to the accompanying drawing, forming a part hereof.

Figure 1 is a perspective view of a windshield scraper and cleaner, showing my new design.

Figure 2 is a top plan view of the windshield scraper and cleaner of Figure 1.

Figure 3 is an end view of the scraper and cleaner of Figure 1. The opposite end being identical is not shown.

I claim:

The ornamental design for a windshield scraper and cleaner, as shown and described.
